US0D1069802S

(12) **United States Design Patent** (10) **Patent No.:** **US D1,069,802 S**
(45) **Date of Patent:** **** Apr. 8, 2025**

(54) **NOTEBOOK COMPUTER**

(71) Applicant: **Getac Technology Corporation**, New
Taipei (TW)

(72) Inventors: **Shuan-Yeong Ju**, Taipei (TW);
Shi-Liang Zhong, Taipei (TW)

(73) Assignee: **Getac Technology Corporation**, New
Taipei (TW)

(**) Term: **15 Years**

(21) Appl. No.: **29/841,510**

(22) Filed: **Jun. 7, 2022**

(51) **LOC (15) Cl.** **14-02**

(52) **U.S. Cl.**

USPC **D14/441**; D14/315

(58) **Field of Classification Search**

USPC D14/314-328, 345-347, 440-441, 250,
D14/444; D13/103, 110, 112, 122,
D13/158-160, 184; D3/282, 900, 902,
D3/905; D9/423, 431, 433; D21/333

CPC G06F 2200/1633; G06F 1/1616; G06F
1/1656; G06F 1/1628

(57) **CLAIM**

The ornamental design for a “notebook computer” as shown and described.

DESCRIPTION

FIG. 1 is a top, front, and right side axonometric view of a notebook computer, showing our new design;

FIG. 2 is a bottom, rear, and left side axonometric view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dash broken lines and any unshaded surfaces in the figures illustrate the portions of the notebook computer that form no part of the claimed design.

1 Claim, 8 Drawing Sheets
